UNITED STATES PATENT OFFICE.

JOHN WILSON CARNES, OF KEWANEE, ILLINOIS.

PIANO ACTION.

Application filed October 1, 1923. Serial No. 665,931.

My invention relates to piano actions, and it consists in the combinations, constructions, and arrangements herein described and claimed.

6 An object of my invention is to provide a piano action for upright pianos, and which is designed to take up less room than other actions of the type, thereby obviating the necessity of extending the piano casing 10 to provide room for mechanical players.

15 A further object of my invention is to provide a piano action in which the parts are simplified, and in which there are fewer parts, without in any way diminishing the effectiveness of the device.

20 A further object of my invention is to provide a piano action, in which the parts may be easily assembled or taken apart for repair or inspection.

25 25 A further object of my invention is to provide a piano action which is more responsive than the ordinary piano action, especially when quick staccato notes are being played, as for instance, in trills where there is a repeated striking of one key. In 30 many pianos, the key may be struck in succession so rapidly that the hammer does not have time to complete its action, owing to the fact that it has to move back a predetermined distance before it can be again thrown forward. The present device provides a construction in which the hammer may be driven forward toward the string again at any point in its backward movement.

35 Other objects and advantages will appear in the following specification, and the novel features of the invention will be particularly pointed out in the appended claims.

40 My invention is illustrated in the accompanying drawings, forming part of this application, in which

45 Figure 1 is a vertical sectional view, showing the piano action in its normal position of rest,

50 Figure 2 is an enlarged sectional view of a portion of the device, showing the parts in position when the hammer has hit the string and has rebounded, while the key is still depressed,

55 Figure 3 is a sectional view showing the position of the parts at the moment the hammer is striking the string, and

55 Figures 4, 5, 6, 7 and 8 are detail views showing parts of the device.

In carrying out my invention, I make use

of the ordinary piano key 1 which, when depressed, raises the abstract 2. The usual abstract flange 3 and abstract flange frame or extension 4 are provided, the latter being 60 mounted on the action bracket 5. The abstract is connected with a wippen 6 which is suspended to the upper-action frame 7, and which bears the usual spoon 8 which engages the lower end of the damper lever 9, 65 the latter being carried at the top of the frame 7, and being provided with the usual damper spring 10. The usual damper lever is provided with a wire 11 which carries the damper 12, the latter normally resting 70 against the strings 13.

The construction thus far described is ordinary. Referring now particularly to Fig. 1, it will be seen that I have provided a jack flange 14 to which is pivoted a jack 75 15. In the ordinary construction, this jack is made in the form of a bell-crank lever. In the present instance, however, it is not so made, but is provided with a jack spring 16 having a coil to add flexibility and durability, which is fastened to the wippen and which extends upwardly beyond the fulcrum point of the jack 15, this spring bearing on the jack toward the upper part thereof, as shown in the drawing, between felt guides 80 85 16^a, which prevent lateral displacement.

It will be seen that the upper-action frame 7 is provided with a recess 7^a near its upper end. A metal loop 17 is passed around the pivot pin 18 of the hammer butt 19, and the end is bent at right angles and is disposed in the recess 7^a. This metal loop is provided with a slot 17^a, through which a screw 20 passes. The metal loop forms a hinge member for the hammer butt 19. The in-turned end prevents the hinge from rotating about the screw 20, while the latter holds the hinge firmly to the upper-action frame. By releasing the screw 20, the hammer butt may be immediately removed from the frame. As will be seen from Figure 2, the hammer butt is provided with an arc-shaped portion 21, having inserts of felt 22, and an arc-shaped felt member 23 arranged to receive the thrust of the upper part of the 105 jack 15. Below the arc-shaped felt member 23 there is a portion 24 of the hammer butt to which is secured a felt strip 25 in the form of a wippen. A trip 26 for the jack is formed by a piece of looped felt which is 110 bound together at its contiguous edges, and which is held by an eye or loop 27^a formed

in a wire 27, one end of which extends into the hammer butt, the other end passing through the felt strip 25, through an opening 28 in the jack, and through an opening 29 in the back catch 30. As will be seen from the drawings, the upper end of the jack is flared outwardly to form a heel at 31, and is provided with a curved portion 32 between the heel and the end. The back catch is pivotally mounted at 33 on an arm 34 carried by the hammer butt, and is provided with a felt cushion 35 arranged to engage the jack. An adjusting screw 36 is provided, having an abutment 37 which is faced with felt for regulating the movement of the jack with respect to the hammer butt. The wire 27 and the connection at 33 holds the back catch rigidly in position.

The normal position of the hammer shank 38 is against the hammer rail 39, thus maintaining the hammer 40 in the position shown in Figure 1.

From the foregoing description of the various parts of the device, the operation thereof may be readily understood. The normal position, as stated above, is that shown in Figure 1. In this position, the upper end of the jack is disposed close to the portion 24 of the hammer butt, with the curved surface 32 contiguous to the trip 26. When the key 1 is depressed, the jack is forced upwardly through the movement of the abstract and the wippen, and this tends to bring the jack and the jack flange more nearly into alignment, thus flexing the jack spring 16. The upward movement of the jack tends to swing the hammer about its fulcrum point 18. The continued upward movement of the jack tends to force it away from the pivot 18, through the medium of the trip 26, so that at the end of the stroke it has reached the position against the abutment and stop 37. The hammer, in the meantime, has been thrown forwardly and has engaged the string, and has rebounded therefrom. In most pianos of this type, it is necessary for the hammer butt to have reached its original position, or substantially so, before the hammer can again be actuated by the key. In this particular construction, however, it is not necessary, since the hammer may be driven forwardly, when the end of the jack is in any position with respect to the arc-shaped portion 21 of the hammer butt, which bears the arc-shaped felt member 23. Pressing on the key, even when the device is in the position shown in Figure 2, will throw the hammer to the string.

The advantage of this construction resides in the facility with which the hammer is enabled to repeat its impacts by successive depressions of the same key at intervals of very short duration. Thus in trills, an expert musician often finds, in the ordinary

piano, that it will not respond quickly enough to enable him to execute a piece of music, where the notes come in rapid succession. In the present instance, however, the hammer will respond with the greatest facility, the reason being that it can be actuated in any position of the jack with respect to the hammer butt, as stated. It does not have to resume its original position in order to again actuate the hammer to throw it forward. This forms the main features of the invention.

It will be noted that the back catch is rigidly held in position by means of the wire 27. This is accomplished by bending the wire at a point 41, where it passes through the back catch, and then hooking it around on the opposite edge at 42. The action is such that when the rebound of the hammer comes, the movement of the hammer butt, at the point where the wire 27 is attached, tends to pull the back catch so as to engage the jack to return it to its normal position.

Another important advantage of my construction over those in which bridle straps are used for insuring the return of the hammer to its normal position of rest, is that in the present construction, the weight of the jack, the wippen, and the abstract, when the pressure of the key is released, tend to swing the hammer butt into its normal position. It will be observed that the wire 27 passes through an opening 28, as stated, in the jack, which is of sufficient size to permit the full action of the jack. When, however, the key is released, the jack will descend, and the wire 27 will be engaged at the upper edge of the opening 28, and the weight of the parts being applied outside of the pivotal point 18, will swing the hammer butt to return the hammer to its original position. In the ordinary structures, having bridle straps or bridle tapes, the hammer may stick, especially where the bearings bind, so that if the bridle strap should be broken for any reason, or eaten through by mice, the hammer may not return to its original position.

A jack form according to the present invention is more certain of action than the one formed in the form of a bell crank lever, and having a coil spring on the short arm, the reason being that the coil spring on the short arm of a bell crank lever tends to exert a thrust, not in the direction in which the jack is to be returned, as in the case of the jack spring, but in such a direction that the pivotal point will bind, in many instances, on its upper edge, thus creating a friction which renders the movement of the jack sluggish. In the present construction, there is no such binding action on the pivotal point of the jack.

Another feature of advantage in the present construction is the ease of the ad-

justment of the throw of the hammer. This can be very readily done by turning the screw 36 so as to limit the movement of the jack.

5. Another feature is the ease with which the parts can be released for inspection or repair. For instance, in removing or tightening the screw 20, it is only necessary to grasp the hooked portion of the wire 27 at 10 the rear of the back catch 30, and to raise it, when the back catch may be swung rearwardly and the jack may be swung also rearwardly, both parts passing off the end of the hook 42, and thus giving full access 15 for a tool, such as a screw driver, to the screw 20.

The construction described eliminates a number of parts that are used in upright pianos, without sacrificing any of the effectiveness of the action. In fact, the action 20 is more responsive for the reasons stated, but this construction takes up a space of about an inch and three-fourths less than the ordinary action, that is to say, measuring 25 from front to rear in a horizontal direction, an inch and three-fourths or thereabouts is saved. This permits more room for the installation of a mechanical player, and obviates the necessity of extending the 30 casing that much.

The elimination of parts renders the construction more economical, which in itself is desirable from the point of manufacture.

I claim:

- 35 1. A piano action comprising a pivotally mounted hammer butt, having an arc-shaped jack-engaging portion, a trip carried by the butt for moving said jack along said arc-shaped portion, means for actuating the jack to cause the hammer to strike the string at any point of engagement of the jack with the hammer butt, a back catch rigidly carried by said hammer butt, and means carried by said back catch for regulating the extent of movement of the jack.
- 40 2. A piano action comprising a pivotally mounted hammer butt, having an arc-shaped jack-engaging surface, a jack arranged to engage said hammer butt and having an opening, a back catch pivoted to said butt and being provided with an opening, and a guide member rigidly secured at one end to said butt and arranged to extend through the openings in said jack and said 45 back catch, one end of said guide member being normally rigidly secured to said back catch.
- 50 3. A piano action comprising a pivotally mounted hammer butt, having an arc-

shaped jack-engaging surface, a jack arranged to engage said hammer butt and having an opening, a back catch carried by said hammer butt, and a guide member arranged to pass through the opening in said jack, one end of said guide member being rigidly secured to the hammer butt, and the other end being rigidly secured to said back catch.

4. A piano action comprising a pivotally mounted hammer butt, having a jack-engaging surface, a wippen, an arm or flange rigidly secured to said wippen, a jack pivotally mounted on said arm, a back catch carried by said hammer butt, and a leaf spring carried by said wippen and arranged to engage the jack above its pivotal mounting to normally force the jack away from said back catch.

5. In a piano action, a wippen, an arm rigidly carried thereby, a jack pivotally carried by said arm, and a leaf spring rigidly secured to one end of said wippen, the other end of said spring having a sliding engagement with said jack beyond its pivotal connection, and means for preventing the lateral movement of the spring with respect to the jack.

6. A piano action comprising a pivotally mounted hammer butt, having an arc-shaped jack-engaging portion, a trip carried by the butt for moving said jack along said arc-shaped portion, means for actuating the jack to cause the hammer to strike the string at any point of engagement of the jack with the hammer butt, a back catch rigidly carried by said hammer butt, and a regulating screw carried by said back catch and arranged to extend through the latter for limiting the extent of movement of the jack toward the back catch.

7. In a piano action, a frame, a hammer butt pivotally mounted on said frame, a back catch pivotally mounted on said hammer butt and having an opening, a trip carried by said hammer butt, a pivotally mounted jack having an opening, a guide wire having one end secured to said butt and arranged to pass through the openings in said jack and said back catch, one end of said guide wire being normally bent downwardly and being rigidly secured to said back catch, said guide wire being flexible, whereby the downwardly bent end may be lifted to permit the pivoted back catch and the pivoted jack to be moved off from said guide wire, thus affording access to the butt-supporting means.

JOHN WILSON CARNES.
